UNITED STATES PATENT OFFICE.

GUSTAV R. SCHIMMEL, OF DETROIT, MICHIGAN.

HYPODERMIC SYRINGE.

No. 844,544.

Specification of Letters Patent.

Patented Feb. 19, 1907.

Application filed April 11, 1904. Serial No. 202,478.

To all whom it may concern:

Be it known that I, GUSTAV R. SCHIMMEL, a citizen of the United States of America, residing at Detroit, in the county of Wayne 5 and State of Michigan, have invented certain new and useful Improvements in Hypodermic Syringes, of which the following is a specification, reference being had therein to the accompanying drawings.

This invention relates to improvements in hypodermic syringes; and its object is to so construct a syringe of this class having a detachable nozzle to receive and hold the needle that a broken needle may be quickly and 15 easily removed, and it is also an object of the invention to provide an attachment whereby the use of a curved needle may be dispensed with.

Referring to the drawings, Figure 1 is a 20 side elevation of a syringe embodying the invention; Fig. 2, an enlarged longitudinal section of the nozzle member and needle; and Fig. 3 an enlarged elevation of one end of the cylinder, showing the nozzle attachment and nozzle in section attached thereto.

A is the cylinder or barrel of the syringe, provided with an externally-screw-threaded nipple A' for the attachment of the nozzle B, which is provided with an internally-screw-threaded socket B' in its enlarged end or head to receive the nipple and an axial bore B² to receive the needle C, an outwardly-extending flange B³ being formed on the head and provided with a milled surface to aid in 35 attaching the nozzle to the nipple. Said needle is provided with a cone-shaped head C', and D is a chamber at the inner end of the socket B', formed with a concave side to form a seat for the conical surface of the 40 head, said chamber being of greater diameter than the diameter of the socket B' and head of the needle, so that should the needle be broken off within the nozzle a headed pin or any suitable instrument may be inserted in 45 the chamber through the socket and hooked beneath the edge of the needle-head to extract the needle. Were it not for the chamber D, when a needle is broken off in the nozzle, as often happens, it would be necessary 50 to punch the needle out, thus subjecting the end of the nozzle to the liability of becoming bent, &c.; but by providing the chamber an opportunity is afforded the operator for get-

ting at the head of the needle, which he would otherwise be unable to do, as the head is made substantially the same diameter as the socket B', so that it will seat properly to prevent leakage around the needle and hold the same firmly in place when engaged by the end of the nipple A'. 55

In order to reach certain parts of the body, as is often the case in dentistry, it is necessary that the needle-point extend at an angle to the cylinder, and in such cases curved needles have heretofore been used; but such needles are 65 difficult to make, very hard to keep clean, and cannot be held in the same manner and by the same nozzle as the straight needles. To obviate these difficulties, I provide a nozzle attachment or curved tubular member E consisting of a metal tube bent to the proper angle and provided at one end with an internally-screw-threaded socket E' to receive the nipple A' and at its opposite end with an external screw-thread E² to engage the 70 socket B' of the nozzle, and thus attach the nozzle to the cylinder in such a manner that it will extend at the proper angle thereto. The same needle and nozzle may thus be 75 used for both straight work and work requiring the angularly-extending needle, thereby lessening the cost of manufacture and greatly facilitating its manipulation.

Having thus fully described my invention, what I claim is— 80

In a hypodermic syringe, the combination with the cylinder having an externally-screw-threaded nipple, of a nozzle formed with an axial bore to receive the needle and an internally-screw-threaded socket to receive the nipple, and with a comparatively 90 large chamber between the inner end of said axial bore and the inner end of said screw-threaded socket, said chamber having its top and bottom walls of conical shape oppositely 95 disposed and meeting to form a wide central space in said chamber, the greatest diameter of said chamber being considerably greater than the diameter of the needle-head.

In testimony whereof I affix my signature 100 in presence of two witnesses.

GUSTAV R. SCHIMMEL.
